J. F. FLANNERY

SASH FASTENER

Filed July 31, 1926

Patented Dec. 13, 1927.

1,652,856

UNITED STATES PATENT OFFICE.

JOHN F. FLANNERY, OF NEWARK, NEW JERSEY.

SASH FASTENER.

Application filed July 31, 1926. Serial No. 126,111.

This invention relates to an improved fastener applicable to various uses but primarily designed as a sash fastener to hold the lower sash against upward movement beyond the 5 point where the fastener is situated in the upper sash.

The invention is designed to provide a fastener which lies normally flat against the side rail of the sash when not in fastening 10 position and which presents a latch and brace to the path of the lower sash when in fastening position, and further, it provides a trip, all these parts being disposed so that when the trip is pressed inwardly by a finger of 15 the person operating it the parts of the fastener assume a fastening position without further manipulation. The trip has another function in that it bears on the bottom of the projected latch to prevent the latch moving 20 downward to release the brace thus making it necessary to positively manipulate the fastener to close it.

The invention also provides a fastener which presents a flat neat appearance when 25 in place and one in which the parts are held secure against rattling in both fastening and closed positions.

The invention is illustrated in the accompanying drawings in which Figure 1 is a 30 perspective view of a fastener in place on an upper sash, the fastener being closed. Figure 2 is a perspective view of the fastener in locking or extended position. Figure 3 is a vertical section through the centre of the 35 fastener showing the fastener closed. Figure 4 is a similar view showing the fastener open or extended and Figure 5 is a section on the line 5—5 in Figure 3.

The moving parts of the fastener are supported in a suitable casing or frame, having 40 side pieces 10 and a front plate 11, the front plate 11 being suitably secured by screws 12 in the face of a side rail 13 of the upper sash of a window. This is the usual installation 45 although it will be evident that it can be affixed at other places, the parts being set in so that the front plate 11 is flush with the outer face of the part to which it is secured so as to provide a neat appearance.

50 Within the chamber formed within the side pieces 10, I arrange a latch 14 which can be moved in or out of the casing, when projected the latch acting as the element against which the part to be fastened abuts 55 and which can be folded within the casing

when in closed position. This is usually done by pivoting the latch on a pin 15.

To hold the latch in its fastening or projected position I provide a brace 16 which is usually pivoted as at 17 so that the brace 60 can be swung outward to engage the latch to hold it in its fastening position. When the parts are folded or closed the brace extends downward substantially flush with the outer 65 face of the casing as shown in Figures 1 and 3, and the latch lies within or behind the brace and is concealed from view. These parts are usually made of sheet metal with side flanges and these provide co-operating 70 parts to hold the latch in extended position by the brace and in the form shown I illustrate the notches 18 in the flanges 19 of the latch which receive the end of the brace as will be evident.

Underneath the latch 14 is a trip 20 which 75 has two functions, one, to limit the downward movement of the latch when the latch is extended or projected and the other is to act as a medium through which the parts of the latch are moved to open or fastening position.

In the form shown the trip is pivoted as 80 at 21 and is provided with a nose 22 that engages with an extension 23 on the latch when the parts are closed. This will be evident 85 from Figure 3. A suitable spring 24 holds the latch yielding in normal position.

When the latch is closed as shown in Figures 1 and 3, and it is desired to open it, a finger of the hand is placed firmly against 90 the upper part of the trip, this pushes the upper part of the trip inward against the influence of the spring 24 and the latch 14 is moved toward its fastening or projected position. As the latch moves out its outer 95 end travels along the two edges 25 on the under face of the brace and thus moves the brace outwardly until the latch has cleared the end of the brace and the parts are in fastening position as shown in Figures 2 100 and 4.

To release the latch to permit the parts to be folded the latch must be moved below its fastening position and to permit this I provide a notch or recess 26 in each side wall of 105 the latch and the trip 20 is moved in slightly so that this notch or recess can ride down over the trip and this permits the latch to be lowered sufficiently to clear the brace and be moved to this position by hand. As soon 110

as the latch is inside the casing, the brace moves to its closed position under the influence of the spring 27.

The pivots 15, 17, and 21, are in the form of pins which also serve to strengthen or brace the side walls of the casing and the U-shaped bracing piece 28 is usually arranged to further strengthen the structure and to act as a support for the spring 27 when the parts are closed. It will be noted that the appearance of the fastener is pleasing as it has the parts pressed in a flat aligned surface. In opening the latch, when the trip is pressed firmly in, the latch and brace are snapped into position and the movements take place instantly and no separate manipulation of the parts is necessary. In closing the latch, however, a more careful manipulation is necessary which is desirable as the closing of the latch by unauthorized persons is therefore made difficult.

The inward movement of the brace is limited by suitable means and I show fingers 29 which engage the inside face of the wall 11 when the brace is in its closed position.

I claim:

1. In a sash fastener, a casing having a recess, a latch pivoted at the recess, a brace pivoted in the recess above the latch, both of these elements swinging outwardly to fastening position and having co-acting means for securing them in fastening position, and a spring for holding the latch in closed position and for holding it against the brace in open position.

2. A sash fastener comprising a latch pivoted to swing outward, a brace pivoted to swing outward to secure the latch in its open position and a trip pivoted below the latch to hold it against downward movement when the latch is open and having a projection to force the latch to open position when it is closed.

3. A sash fastener comprising a frame, a latch in the frame and supported so that it can be projected from the frame and also made to lie within the frame, a brace pivoted

to the frame, the latch and brace having co-operating parts to hold them in fastened relation when the latch is projected, the latch having a part to bear on the brace to move the brace outward when the latch is projected, and a trip under the latch and having a part to project the latch, the trip acting as an abutment for the projected latch. 55

4. A sash fastener comprising a frame, a latch, a brace, a trip, the brace and the trip having flat faces to lie in alignment with the frame and being pivoted thereto, a nose on the trip to project the latch, the end of the latch bearing on the brace to move the latter outward when the latch is projected, whereby all the parts assume a fastened position when the trip is operated, and a spring to yieldingly hold the trip in normal position 60 to limit the projected position of the latch.

5. A sash fastener comprising a frame, a latch, a brace, a trip, the brace and the trip having flat faces to lie in alignment with the frame and being pivoted thereto, a nose 70 on the trip to project the latch, the end of the latch bearing on the brace to move the latter outward when the latch is projected, whereby all the parts assume a fastened position when the trip is operated, and a spring to yieldingly hold the trip in normal position 75 to limit the projected position of the latch, and a spring bearing on the brace to return it to closed position when it is released from the latch. 80

6. A sash fastener comprising a frame, a spring pressed trip in the frame, a latch pivoted above the trip in the frame, a latch pivoted above the trip and disposed so as to be projected when the trip is pressed and a brace pivoted above the latch and lying normally in front of it and disposed so as to be moved outward by the projected latch, the brace and latch having coacting parts to hold them secured in extended position. 85 90

In testimony whereof I affix my signature.

JOHN F. FLANNERY.
